UNITED STATES PATENT OFFICE

MICHAEL KUPINSKY COOPER, OF LIVERPOOL, ENGLAND

VACUUM CLEANER

Application filed January 16, 1928, Serial No. 247,023, and in Great Britain January 19, 1927.

This invention relates to hand-actuated vacuum cleaning machines, and has for its object to provide a machine which shall be simple in construction, and so may be cheaply manufactured, and of high suction efficiency.

A vacuum cleaning machine, according to my invention, essentially includes a pair of suction fans disposed in separate housings and driven from wheel, and a suction mouth-piece and dust discharge passage communicating with said housings.

Provision is preferably made for the automatic disengagement of the floor driving wheel from the fans on the reversal of travel of the machine, so as to ensure continued rotation of the fans in the operative direction.

In one construction said fans are carried by a horizontal shaft or spindle, said shaft being adapted to be operated by a friction floor wheel which also operates—through a friction pinion—a brush, or the like, disposed in the suction mouthpiece.

Other and additional features are herein-after described and pointed out in the claiming clauses concluding this specification.

I will further describe my invention with the aid of the accompanying sheets of explanatory drawings which illustrate by way of examples only, two modes of embodying same.

In said drawings:—

Figs. 1 to 4, inclusive, illustrate a hand-actuated vacuum cleaning machine according to one construction;

Fig. 1 being a longitudinal section of the machine, Fig. 2 an end view, Fig. 3 a transverse section taken on line A—A Fig. 1, and Fig. 4 a section of a fragmentary portion of the machine.

Fig. 5 illustrates a machine of modified construction.

In the several views like characters of reference denote like or equivalent parts wherever they occur.

Referring to said drawings, but first more particularly, to Figs. 1 to 4, inclusive, 1 generally indicates the machine, the casing 2 whereof is constructed in two parts secured together by means of studs 3 to provide two

separate housings 4, each of which housings communicate by way of a conduit 5 with a suction nozzle 6, and with a common discharge passage 7 whereto a dust bag 8 is detachably secured by means of a band or clip 9. 55

Disposed in each of said housings 4 is an air suction fan 10, said fans being secured to a shaft 11 which is revolvably mounted in ball bearings 12 and is milled, knurled, toothed or otherwise serrated, in order to create a 60 frictional gripping surface for a fan operating rubber tyred floor wheel 13.

Said wheel 13—which is adapted to automatically disengage from said fan-carrying-shaft 11 on the reversal of travel of the machine so as to prevent rotation of the fans in the reverse and so inoperative direction—is mounted on a spindle 14 at the lower end of a fork 15, the upper end of which fork is carried in a pivotal manner on a pin 16 fixed to a 70 channel member 17, for this purpose.

Said channel member is secured to a rod 18 screwed through a tapped boss 19 formed in casing 2 and is provided with a knob 20: thus, by turning knob 20 the suction nozzle 6 of 75 the machine may be vertically adjusted as desired, whilst twisting or displacement of fork 15 and wheel 13 is prevented by lugs 21 which form guide grooves 22 wherein ends of pin 16 are entered. 80

Located in the suction nozzle 6 of the machine is a brush 23 of bristles, rubber, or other suitable material, the spindle 24 whereof is mounted in elongated slots 25 formed in a pair of plates 26 adjustably attached in the 85 nozzle by means of studs 27 wherein small rollers 28 are provided in order to support the front of the machine. A rubber pinion 29 fixed at the centre of said brush spindle 24 is held in frictional engagement with wheel 13, 90 in order to rotate the brush, by means of springs 30 disposed in apertures 31 of plates 26 and adapted to bear on suitable lubricating blocks 32 which engage the spindle ends. Therefore, brush 23 will be continuously rotated from wheel 13 irrespective as to whether the latter is in engagement with the fan-carrying-shaft 11, or not, and said brush may be vertically adjusted when the bristles are worn, in order to enable same to be complete. 95

ly utilized, by turning plates 26 about studs 27; whilst the frictional engagement of said pinion 29 with floor wheel 13 may be regulated by set screws 31.

5 Rubber tyred wheels 33, mounted on an axle 34 in lugs 35 cast on the housings 4 of casing 2 support the rear of the machine; and a pivotal frame 36, whereto a handle is, or may be, attached, is adapted for operating the machine.

10 Assuming the machine is being moved from rest in a rearward or inoperative direction (when the parts will be in the positions shown in Fig. 1) floor wheel 13 is disengaged from shaft 11, therefore the fans 10 are stationary, whilst pinion 29 of spindle 24, due to the influence of springs 30, is in frictional contact with said floor wheel, and brush 23 is being rotated. Immediately the direction of 15 the machine is reversed, floor wheel 13, through spindle 14 and fork 15, swivels about pin 16 into frictional engagement with shaft 11, so that fans 10 are revolved: at the same time, brush 23 is being rotated, as spindle 24— 20 acting under the influence of springs 30— moves in slots 25 of plates 26 and maintains wheel 29 in frictional engagement with floor wheel 13.

25 The machine is now moving in its operative direction, and dust is loosened by brush 23 and drawn into the nozzle 6 from whence it is carried by the suction created by fans 10 through conduits 5 into housings 4, and ejected therefrom by said fans, in their continued revolution, through the discharge passage 30 into bag 8.

35 Referring now to the modified machine illustrated in Fig. 5, wheel 13 is carried by a pair of arms or links 37, which links are pivotally attached at 38 to casing 2 and are connected by means of a rod 39 with the brush spindle 24 adapted to be rotated by means of wheels 40, and being longitudinally movable in slots 41. Said rod 39 controls the disengaging movement of floor wheel 13, and may 40 be adjusted by means of a finger-screw 42. The forward movement of the machine causes—through the resistance of wheels 40 with the floor, as transmitted by rod 39—the links 37 to swivel on pivot 38 and move wheel 13 into engagement with fan carrying shaft 11 to rotate fans 10.

45 It will, of course, be understood that various other modifications or changes may be made without departing from the spirit and scope of the invention as defined by the claims.

50 What I claim as my invention and desire to secure by Letters Patent is:—

55 1. A hand-actuated vacuum cleaning machine including a housing, a fan mounted therein, a nozzle at one end of said housing, a brush rotatably mounted in said nozzle, a shaft carrying said fan, a floor wheel pivotally mounted between said shaft and brush,

whereby said wheel is brought into engagement with said shaft on forward motion of the machine and disengaged therefrom on rearward motion, a pinion carried by said rotatable brush, and spring means normally holding said pinion in engagement with said floor wheel.

60 2. A hand-actuated vacuum cleaning machine including a housing, a fan mounted therein, a nozzle at one end of said housing, a brush rotatably mounted in said nozzle, a shaft carrying said fan, a floor wheel pivotally mounted between said shaft and brush, whereby said wheel is brought into engagement with said shaft on forward motion of the machine and disengaged therefrom on rearward motion, and means for adjusting the elevation of said housing relatively to said floor wheel.

65 In testimony whereof I affix my signature. 85
MICHAEL KUPINSKY COOPER.
